COOLING SYSTEM FOR INTERNAL COMBUSTION ENGINES WITH LIQUID COOLING

Fritz Nallinger, Stuttgart, Germany, assignor to Daimler - Benz Aktiengesellschaft, Stuttgart-Unterturkheim, Germany

Application August 31, 1938, Serial No. 227,613
In Germany September 6, 1937

9 Claims. (CL 123—174)

The invention relates to a cooling system for internal combustion engines with liquid cooling by means of liquids with bad heat transition, especially glycol cooling, and has for its object to 5 avoid the difficulties due to bad heat transition and to the low specific heat of such liquids.

Instead of glycol e. g. also glycerine or mineral oils are used.

It has been endeavoured to obtain better results 10 with glycol cooling, by more advantageous feeding of the cooling medium in the cylinder, by special ribs and the like, without such cooling having given full satisfaction. The endeavours to avoid the existing disadvantages by simple means have 15 resulted in that for obtaining a more intensive cooling effect while retaining the ordinary cooling systems, simply the quantity in circulation of cooling liquid, that is of the glycol, has been increased. Such an increase is, however, limited in 20 the radiators because in the case of large circulating quantities these radiators must be given too large passage cross-sectional areas and consequently their degree of efficiency drops.

These disadvantages are overcome according to 25 the invention in that a large sized suction and pressure pump maintains the cooling liquid in uninterrupted circulation through the cooling spaces of the engine and a secondary circulation is deflected from the suction conduit of the pump 30 by which only a portion of the circulating liquid is returned through the radiator to the main circulation, so that in the case of small dimensioned radiator, the largest possible quantity of liquid can be conducted through the engine. The particular advantages are therefore obtained owing 35 to the fact that for the cooling liquid flow, two circulations are provided, one of which effects the circulation of the cooling liquid in the engine itself, whereas the other circulation, deflected from the first one, conducts a part flow of cooling 40 liquid through the radiator of ordinary dimensions. A separate pump or pumping system may be provided for each circulation or also this part flow can be branched off to the radiator through correspondingly dimensioned nozzles or pipe conduits. When two pumps viz. pumping systems 45 are employed, the feed pump effecting the cooling water circulation in the engine must be larger than the pump viz. pumping system provided for the part flow through the radiator. A large quantity of cooling liquid is conducted through the cooling spaces at a high speed of flow by the large cooling liquid pump effecting the internal circulation in the engine, so that the heat exchange 50 between the engine and the cooling liquid is very

intensive. For re-cooling the liquid charged with heat a smaller part flow is then separated from the main circulation and conducted through the radiator which can consequently be of normal dimensions and have a high degree of efficiency. 5 It is clear that there must be a certain ratio between the amount of liquid circulating through the engine and the dimensions of the radiator to ensure a good working of the system, this ratio depending on the average amount of heat produced by the engine and the specific heat and heat conductivity of the liquid used.

Instead of using two pumps viz. pumping systems of different sizes, a single large pump or pumping system may also be provided which 15 effects the circulation in the main cooling flow and from which a part flow is branched off to the radiator through suitably dimensioned nozzles or pipe conduits. Instead by means of such a nozzle the amount of liquid circulating in the part flow 20 may also be determined by the output of the pump. Means to adjust the output of the pump are then provided. For suitably regulating the part flow through the radiator an adjustable throttle element is preferably fitted in the suction 25 conduit.

It is immaterial for the invention whether glycol or some other suitable cooling medium, possibly also water with an addition, is used. The essential point is only that a large flow of liquid 30 is conducted through the cooling spaces of the engine and that only a part flow passes through the normally dimensioned radiator, so that its degree of efficiency remains within reasonable limits. It is furthermore essential that a large 35 and efficient pump—or two such pumps—are used, viz. pumping systems.

Several embodiments of the invention are illustrated by way of example in the accompanying drawing, in which:

Fig. 1 shows a cooling system for internal combustion engines with two cooling pumps,

Fig. 2 is a similar arrangement with only one cooling pump from whose suction conduit a part flow is branched off to the radiator.

An internal combustion engine *a* is equipped with a radiator *b* and with pumps *c* and *d* for the cooling liquid which pumps are driven from the main shaft of the engine for example through the intermediary of bevel wheels *q*. For the internal cooling liquid circulation of the engine the large sized pump *c* is provided which forces the cooling liquid through a pipe *h* to the cooling spaces of the engine and thence sucks it back through a pipe *i*. From the pipe *i* a pipe *m* 50

45

50

55

branches, through which a portion of the cooling liquid is deflected and returned by the pump *d* to the main pressure pipe *h* through the radiator *b* and pipes *n*, *k*. The suction pipe *i* may be provided for example with a throttle or shut-off valve *f*.

In Fig. 2 similar parts have the same references as in Fig. 1. Only a single large sized pump *c* is provided which may also be driven from the main shaft of the internal combustion engine through the intermediary of bevel wheels *q*. From the suction pipe *i* a pipe *l* branches off to the radiator *b* which pipe *l* may have for example a throttle point *e*, or be chosen of corresponding cross-sectional area. Furthermore an adjustable throttle element *g* may be fitted in the suction pipe *i* after the point where pipe *e* branches off. The quantity of liquid flowing through the radiator can be accurately regulated by this throttle element *g*. After passing through the radiator *b* the part flow is returned through a pipe *o* to the main flow, in the pipe *i* and thence fed by the pump *c* to the cooling spaces of the engine *a*.

By the cooling system according to the invention the hot cooling liquid of the main circulation *c*, *h*, *a*, *i* is repeatedly mixed with the portion of the liquid re-cooled in the radiator *b* and thus a cooling temperature is obtained which changes within permissible limits.

Having now particularly described and ascertained the nature of my said invention and in what manner the same is to be performed, I declare that what I claim is:

1. A cooling system for internal combustion engines with liquid cooling by means of liquids with bad heat transfer comprising a liquid pump of large capacity, means to drive this pump, a pipe leading from the cooling spaces of the engine to this pump, a pipe leading from the upper part of the engine to the suction side of the pump, a radiator, a pipe leading from the upper part of the radiator to the pipe connecting the upper part of the engine with the suction side of the pump, a nozzle in this part of the pipe system, finally a pipe connecting the lower part of the radiator with the suction side of the pump.

2. A cooling system for internal combustion engines with liquid cooling by means of liquids with bad heat transfer comprising a pump of large size, means to drive this pump, a pipe leading from the cooling spaces of the engine to this pump, a pipe leading from the upper part of the engine to the suction side of the pump, a radiator, a pipe leading from the upper part of the radiator to the pipe connecting the upper part of the engine with the suction side of the pump, a nozzle in this part of the pipe system, finally a pipe connecting the lower part of the radiator with the suction side of the pump, a throttle element being provided in the pipe leading to the upper part of the engine between the points where the pipes from the radiator discharge into this pipe.

3. A cooling system for internal combustion engines with liquid cooling by means of liquids with bad heat transfer comprising a pump of large size, means to drive this pump, a pipe leading from the cooling spaces of the engine to this pump, a pipe leading from the upper part of the engine to the suction side of the pump, a radiator, a pipe leading from the upper part of the radiator to the pipe connecting the upper part of the engine with the suction side of the pump, means to adjust the output of the pump, finally a pipe connecting the lower part of the radiator with the suction side of the pump.

4. A cooling system for internal combustion engines with liquid cooling by means of liquids having low heat transmission, comprising the combination, with a main circulation and a cooler connected thereto, of a liquid pump of large capacity delivering the cooling liquid into the main circulation through the cooling spaces of the engine and a second liquid pump of relatively smaller capacity with an auxiliary circulation delivering only a limited part of the circulating liquid through the cooler to the main circulation, the limited part of the auxiliary circulation being smaller than the remaining part of the main circulation.

5. Cooling system for internal combustion engines with liquid cooling by means of liquid cooling media with bad heat transfer, comprising two liquid pumps of different output capacities, means for driving the two pumps, a cooling liquid pipe of large dimensions for the entire cooling liquid comprising a pipe leading from the output portion of a cooling chamber of the engine involved to the suction side of the larger pump and a return pipe from the delivery side of said larger pump to the receiving portion of the engine cooling chamber, a smaller pipe for a part of the entire circulating cooling liquid branching off from the pipe between the upper part of the engine and the suction side of the larger pump comprising a radiator, a pipe leading from the branching point on the large pipe of the cooling liquid to the upper part of the radiator, a pipe leading from the lower side of the radiator to the suction side of the smaller pump and a pipe leading from the delivery side of the smaller pump to the delivery side of the larger pump, and a throttling member in the suction pipe of the larger pump between the branching point of the smaller pump and the suction pipe connection of the larger pump.

6. A cooling system for internal combustion engines with liquid cooling by means of liquids having low heat transmission, comprising the combination, with a main circulation and a cooler connected thereto, of a liquid pump of large capacity delivering the cooling liquid into the main circulation through the cooling spaces of the engine and a second liquid pump of relatively smaller capacity with an auxiliary circulation delivering only a limited part of the circulating liquid through the cooler to the main circulation.

7. In a cooling system for internal combustion engines with liquid cooling by means of cooling liquid media with bad heat transfer having two liquid pumps, and a radiator, there being means for driving the pumps, the combination of a conduit connected at one end with one portion of the engine in communication with the cooling spaces therein and at the other end with another portion of said engine likewise communicating with said cooling spaces, said conduit and cooling spaces forming a closed circuit with one of said pumps included in said circuit and a throttling member likewise included in said circuit, a second closed circuit including a conduit connected at the two ends thereof to the first mentioned circuit so as to form a shunt circuit therefor and having the second pump and said radiator included in said second circuit, said throttling member in the first circuit positively controlling the flow of liquid not only through the first pump, but also the liquid flowing through the second pump and the radiator by limiting the flow in said first circuit.

8. A cooling system according to claim 7, in which the output capacities of the two pumps are

different so that the first pump has a larger output capacity than the second pump.

9. In a cooling system for internal combustion engines with liquid cooling by means of cooling liquid media having poor heat transfer and having pump means and a radiator, there being means for driving the pump means, the combination of a conduit connected at one end with one portion of the engine in communication with the cooling chambers therein and at the other end with another portion of said engine likewise communicating with said cooling chambers, said conduit and cooling chambers forming a closed circuit with at least part of the pump means included in said circuit and a throttling member also included in said circuit, a second closed circuit including a conduit connected at the two ends thereof to the first mentioned circuit so as to form a shunt circuit therefor and having said radiator included in said second circuit, said throttling member in the first circuit positively controlling the flow of liquid not only through the first circuit, but also the flow of liquid through the second circuit and the radiator by limiting the flow in said first circuit. 5 10
